MILLIMETER WAVE GENERATING REFLEX
KLYSTRON

Hubert Leboutet, Paris, France, assignor to Compagnie Generale de Telegraphie Sans Fil, a corporation of France

Application May 13, 1955, Serial No. 508,090

Claims priority, application France May 18, 1954

7 Claims. (Cl. 315—5.22)

The invention relates to millimeter wave generators using reflex klystrons.

It has already been proposed to obtain a millimeter wave generator tube of the reflex klystron type by so selecting the size of its cavity resonator that its fundamental resonant frequency corresponds to the desired millimeter wave. Practically insurmountable difficulties have been encountered, however, owing to the small geometric dimensions required for the various constituent parts of the tube. For example, a cavity resonator of the rhumbatron type dimensioned for resonance at a fundamental frequency of 3 mm. would have all its dimensions equal to, at the most, 1.5 mm. These small dimensions necessitate very thin electron beams and thus very weak electronic currents.

It has also been proposed to obtain millimeter waves by utilizing a centimeter wave klystron generator followed by a series of crystal frequency multipliers. This system, however, only affords very low power which is always less than the power furnished at the fundamental frequency by the klystron. Furthermore, the generating device is extremely complicated.

The object of the present invention is to provide a reflex klystron device oscillator dimensioned for a fundamental frequency of oscillation pertaining to the range of centimeter waves and designed in such manner that at least one of its harmonics pertaining to the range of millimeter waves and, in consequence, of the order of at least 10, is favored, only the energy corresponding to this harmonic being collected at the output of the tube.

The invention will be more clearly understood from the ensuing description with reference to the accompanying drawings in which:

Fig. 1 is an axial sectional view of the klystron embodying the invention.

Fig. 2 is a cross-sectional view, taken along line II—II of Fig. 1, of the elements of the klystron situated above this section.

The reflex klystron shown in Fig. 1 has a structure of revolution. It comprises at its lower part a cylindrical metal envelope 1 in the form of a body of revolution closed at its lower part by a glass envelope 2 and at its upper part by a hollow truncated cone 3 of metal which is supported by the envelope 1 through the medium of a metal ring 40 and is provided at its lower and upper ends with a first opening 43 and a second opening 13. A cavity resonator 41 in the shape of a rhumbatron is bounded by the conical element 3, a flat metal element 4, and deformable metal walls 5. A third opening 15 formed in the element 4 is in axial alignment with the two first-mentioned openings 43 and 13.

Coaxial with the tube and disposed inside the cylindrical envelope 1, is an electron gun comprising a cathode 6, heated by a filament 7, and an anode 8. The supply leads for the electrodes 6, 7 and 8 extend through the glass envelope 2 and are respectively supplied by a source of direct current voltage 9, in the case of the fila-

2

ment 7, and a source of direct current voltage 10 adjustable by means of a potentiometer 11, in the case of the anode 8.

The upper part of the reflex klystron comprises a cylindrical metal envelope 17 fixed to the metal element 4 and closed at its upper part by a glass wall 18.

The interior of the three portions 1, 41 and 17 is evacuated.

A metal rod 42 coaxial with the tube and disposed inside the cylinder 17 supports a reflector 19 whose distance to the upper base of the cone 3 is designated by h . A source 20 supplying a continuous voltage adjustable by means of a potentiometer 21 applies to the reflector 19 the appropriate direct current negative voltage.

As the walls 5 of the cavity resonator 41 are deformable, the distance d between the two openings 13 and 15 inside the cavity resonator may be varied. The adjustment of the distance d is ensured by a mechanism of known type comprising a housing 22 fixed to the metal envelope 1 enclosing the gun 6 by means of a plate 23 rigidly connected to this envelope. The housing 22 encloses a ring 24 provided with external teeth and an internal screw thread; this ring 4 is rotatable between balls 25. The internal screw thread meshes with a ring 26 rigid with the envelope 17. The outer periphery of the ring 24 meshes with a worm gear 27. On rotating the latter, the ring 26 is angularly displaced about its axis and the elements 17 and 4 unitary with this ring move with the latter, the elements 1 and 3 remaining stationary. The wall 5 is deformed and the distance d is varied.

The above-described elements are similar to those to be found in reflex klystrons of known type. The klystron embodying the invention is new in so far as concerns the special structural features now to be described.

The opening 13 is provided with two groups of four radial fins 14 and 14', the two groups having different radial dimensions $\lambda_1/2$ and $\lambda_2/2$ respectively, of the order of one millimeter. Provided below this opening in the inner wall of the hollow metal cone 3, is a wave trap 33. The opening 15, which has preferably a diameter slightly greater than the opening 13, is also provided with two groups of four fins 16 and 16', the dimensions being substantially $\lambda_1/2$ for the first, and $\lambda_2/2$ for the second group, as shown in Fig. 2.

The cavity resonator 41 is provided with five microwave outputs as shown in Fig. 2: an output 30 so dimensioned as to transmit energy corresponding to its fundamental frequency range of oscillation centered on a wavelength λ_0 in free space and two pairs of outputs 28 and 29 respectively dimensioned for transmitting two ranges of wavelengths both inferior to $\lambda_0/10$ and respectively centered on λ_2 and λ_1 , the wavelengths λ_1 and λ_2 being equal to the above-defined dimensions λ_1 and λ_2 . The output 30 is a coaxial antenna terminating in the cavity resonator 41, in a loop 39, the plane of which is perpendicular to the plane of Figure 2. It is loaded to an adjustable impedance 34 through a matching device 35 which is so adjusted that the load impedance seen at the output of the antenna is a practically pure reactance.

The outputs 28 and 29 are constituted respectively by two pairs of wave guides, the two guides of each pair having the same section and the guides of one pair 28, for example, having a section greater than the guides of the other pair 29. Each guide is closed by a very thin glass window 36. In the specific example shown in Fig. 2, the useful energy in the range λ_1 is obtained from the guide 29 having an axis OA, the other guides terminating in a short-circuit piston 37. The tube could be adjusted, as hereinafter explained, so as to operate on a lower output frequency comprised in the range of λ_2 . The guides 29 could then be closed and the energy obtained from one of the guides 28.

Two coils 38 are disposed around the tube for producing a weak axial magnetic field 4 (Fig. 1).

The main dimensions of the klystron shown in Fig. 1 are governed by the following parameters:

a designates the outside radius of the upper base of the cone 3.

b designates the radius of the cavity resonator.

d is the above-mentioned distance between the openings 13 and 15 inside the cavity resonator.

h is the above-mentioned distance between the reflector and said upper base.

l is the mean distance between the plate 4 and the flexible deformable wall 5.

The above-described klystron operates in the following manner:

The electron beam produced by the cathode 6 follows, under the action of the accelerating voltage of the anode 8, a path passing through in succession: space 32 inside the envelope 1 between the anode 8 and the opening 43, and the space 31 inside the hollow metal cone 3. The beam thereafter enters the cavity resonator 41 through the opening 13. It passes through this cavity resonator in which it is velocity modulated in a direction parallel to the axis of the tube and emerges from the opening 15. It approaches the reflector 19 and the latter, brought to a negative potential, repels the beam which follows, in the opposite direction, a path parallel to that which it had just followed, entering the cavity resonator 41 through the opening 15 and emerging therefrom through the opening 13. As is well-known, a density modulation of the beam occurs in the space between the plate 4 and the reflector 19. A high frequency field having components of various resonant frequencies is produced and is maintained in the cavity resonator 41 by the bunched beam. The above-described operation is similar to that of a conventional reflex klystron. The characteristics of the klystron embodying the invention as concerns dimension, adjustment and operation will now be described.

The cavity resonator is so constructed and dimensioned to fulfill the following conditions:

(1) The cavity is capable to resonate, whatever the distance *d* may be, within its limits of variation, on certain nearly constant frequencies, corresponding to higher modes, in the two ranges around λ_1 and λ_2 .

(2) The cavity is tunable, the fundamental frequency depending upon the adjustment of distance *d*, comprised for example in the centimeter range.

(3) For a few values of the distance *d*, certain of said fixed higher frequencies are true harmonics of the fundamental frequencies corresponding respectively to said values.

(4) The cavity is capable of providing an important part of the energy at said fixed frequencies, in its reentrant portion, so as to allow interaction between the beam and said energy.

It has been found that when these results are obtained, the following equation (which is an approximate equation but nevertheless valid over a large range) established by the applicant:

$$\frac{pb}{\lambda_0} = \frac{\epsilon m}{2.62(m-1)} + \left(1 - \frac{\epsilon}{m-1}\right) \sqrt{\frac{n^2(b/l)^2}{4} + \frac{k^2(m/(m-1))^2}{4}}$$

is satisfied with integers $n \geq 0$, and $k \geq 1$.

In this equation: λ_0 (wavelength in free space of the fundamental frequency) being given, the sizes of the cavity resonator are calculated in a known manner, for example from the annex B of the work "Klystron Tubes" by A. E. Harrison, 1947:

$$p = \frac{\lambda_0}{\lambda}$$

designates the order of harmonics it is desired to generate.

e Is equal to

$$\frac{d}{l}$$

5 and *m* is equal to

$$\frac{b}{a}$$

The values of the various parameters in this formula, 10 which depend on the dimensions of the klystron, have been so selected in the construction of the latter that while adjusting the values of *d*, by means of screw 27, it is possible to obtain a few number of groups of satisfactory values for *n* and *k*. Thus, for a certain number of particular values of *d*, an harmonic of an order greater than 10 of the fundamental frequency is generated.

Finally, the tube is capable of producing a certain number of given harmonic frequencies, of order greater than 10; therefore *d* is adjusted so as to obtain a given fundamental frequency, an harmonic of which corresponds to the desired output wavelength λ_u . After λ_u has thus been selected, the following adjustments must be performed:

25 The voltage of the reflector is first adjusted by trial and error, and contingently, the load 34 connected to the output 30.

It is found that for a given dimensioning of the cavity resonator, several ranges of voltage of the reflector exist, 30 each corresponding to a given adjustment of the load on the fundamental frequency. In particular, within the range corresponding to λ_u , there exists a critical value of voltage giving rise to a considerable harmonic power on λ_u . Taking into account the desired high order of 35 this harmonic, the value to which the reflector voltage is finally adjusted is generally situated near the threshold of the building up of fundamental oscillation.

Generally the impedance 34 is adjusted, for convenience, in the neighborhood of a pure reactance for the 40 oscillation λ_0 , though this last condition is not, strictly speaking, necessary.

The distance *h* between the reflector and the upper edge of the opening 13 is not critical. This distance is calculated, when designing the tube, and has a value equal 45 to an integer number of λ_2 , λ being comprised between λ_1 and λ_2 . This distance *h* favors the generation of waves in the ranges λ_1 and λ_2 . In the same manner, the trap 33 favors waves in the ranges λ_1 and λ_2 , if its depth is comprised between

$$50 \quad \frac{\lambda_1}{4}$$

and

$$\frac{\lambda_2}{4}$$

55 It may be assumed that the reflected waves in the ranges λ_1 and λ_2 are therefore totally reflected by this trap and this reflector and return toward the cavity resonator, while the other waves continue to be propagated in the direction 60 of the cathode and are not reflected by the reflector. The beam is therefore modulated by the wave in the ranges of λ_1 and λ_2 under the most favorable conditions. The fins 14-14', 16-16' favor the coupling between the beam and the waves in the ranges of λ_1 and λ_2 respectively.

65 The magnetic field *H* is also selected by trial and error for increasing the output on the desired harmonics.

Finally in the klystron, according to the invention, the diameter of the beam is of the order of one useful wavelength, whereas that of the cavity resonator is of the order 70 of five times the useful wavelength. The latter is therefore readily obtained and, furthermore, the building up condition of the oscillations in the cavity resonator instead of occurring in respect of a millimeter wavelength occurs in respect of a centimeter wavelength; it is therefore easily satisfied.

The invention is not intended to be limited to the above-described specific embodiment.

What I claim is:

1. A reflex klystron oscillator for millimeter waves having an evacuated and elongated envelope comprising a first cylindrical portion having a first and a second end, a first plate perpendicular to its cylindrical axis, closing said first end, extended at its center by a hollow conical axially positioned member and terminated by a first aperture and a second aperture at its two respective ends; a second cylindrical portion coaxial with said first cylindrical portion, having a first end and a second end, a second plate perpendicular to its cylindrical axis closing its first end and having a third axially positioned aperture; a third portion constituting a cavity resonator bounded by said first plate, said hollow conical member and deformable walls; said cavity resonator being dimensioned for resonating at a fundamental frequency and at least at one predetermined higher frequency, in the millimeter range, and having a gap bounded by said second aperture and said third aperture; said oscillator further comprising: means for deforming said deformable walls to tune said cavity resonator to a fundamental frequency which is a subharmonic of said predetermined higher frequency of an order at least equal to ten; said first cylindrical portion including a source of electrons mounted adjacent said first aperture for projecting a beam of electrons through said hollow conical member, said gap and said third aperture; said gap being dimensioned for coupling said beam and ultra-high frequency wave at said higher frequency; said second cylindrical portion including a reflector electrode for reflecting electrons back through said third aperture, said gap, and said conical member; at least a first output for energy at said fundamental frequency and at least a second output for energy at said higher frequency. 35

2. A reflex klystron oscillator as claimed in claim 1, in which said first output is loaded by a pure reactance.

3. A reflex klystron oscillator as claimed in claim 1, in which said second output comprises at least one wave guide dimensioned to transmit said higher frequency.

4. A reflex klystron oscillator as claimed in claim 1, in which said second and said third apertures are provided with at least one group of radial fins, each of said groups having a radial dimension substantially equal to half the wavelength in free space of a particular higher resonance frequency of said cavity resonator and said second output comprising wave guides dimensions for said particular higher frequencies. 10

5. A reflex klystron oscillator as claimed in claim 1, 15 in which the distance between said reflector electrode and said second aperture is substantially equal to an integer number of half wavelengths corresponding to said higher frequency.

6. A reflex klystron oscillator as claimed in claim 1, 20 said hollow conical member comprising an outer wall and an inner wall in which is arranged a wavetrap having a depth substantially equal to a quarter wavelength of said higher frequency.

7. A reflex klystron oscillator as claimed in claim 1, 25 further comprising means for generating a magnetic field of comparatively low intensity and substantially parallel to said axis.
